ROTARY HOE

William G. Moore, Albany, Ga., assignor to
Lilliston Corporation, Albany, Ga.

Continuation-in-part of design applications Ser. No.
24,251 and Ser. No. 24,252, July 31, 1970. This
application Apr. 22, 1971, Ser. No. 136,641

Term of patent 14 years

Int. Cl. D15—03, 99

U.S. Cl. D39

FIG. 1

FIG. 3

FIG. 2

FIG. 4

FIG. 5

FIG. 6

FIG. 7

FIG. 9

FIG. 8

FIG. 10

FIG. 11

FIG. 12

FIG. 1 is an elevational view showing one side of the rotary hoe.

FIG. 2 is an elevational view showing the side of the rotary hoe opposite the side shown in FIG. 1.

FIG. 3 is an end view of the rotary hoe shown in FIG. 2.

FIG. 4 is a cross-sectional view taken along the line 4-4 in FIG. 1.

FIG. 5 is a cross-sectional view taken along the line 5-5 in FIG. 1.

FIG. 6 is a cross-sectional view taken along the line 6-6 in FIG. 1.

FIG. 7 is an elevational view showing one side of the rotary hoe slightly modified.

FIG. 8 is an elevational view showing the side of the rotary hoe opposite the side shown in FIG. 7.

FIG. 9 is an end view of the rotary hoe shown in FIG. 8.

FIG. 10 is a cross-sectional view taken along the line 10-10 in FIG. 7.

FIG. 11 is a cross-sectional view taken along the line 11-11 in FIG. 7.

FIG. 12 is a cross-sectional view taken along the line 12-12 in FIG. 7.

This application is a continuation of my copending applications, Ser. Nos. 24,251 and 24,252, both filed July 31, 1970 and now abandoned.

I claim:

The ornamental design for a rotary hoe, as shown and described.
